MULTIPLE CIRCULATION BOILER

Filed Oct. 12, 1925

UNITED STATES PATENT OFFICE

HENRY JOHN SUTHERLAND MACKAY, OF LONDON, ENGLAND, ASSIGNOR TO THE BAB-COCK & WILCOX COMPANY, OF BAYONNE, NEW JERSEY, A CORPORATION OF NEW JERSEY

MULTIPLE CIRCULATION BOILER

Application filed October 12, 1925, Serial No. 61,875, and in Great Britain December 15, 1924.

This invention relates to a boiler in which a plurality of water circulation systems or circuits is used and in which furnace gases of different temperatures contact with the respective systems, and will best be understood from the description in connection with the accompanying drawings, in which Fig. 1 is a longitudinal section through the boiler and Fig. 2 is an elongated longitudinal section 10 through the rear steam and water drum.

This invention is especially adapted to steam generators of the drum and water tube type, including top and bottom drums so disposed and connected as to provide separate 15 and distinct circuits between the top and bottom drums, and a common circuit between the top drums. Heretofore, in steam generators of this type, the feed inlet has been located in one of the bottom or mud drums, or 20 the feed water has been introduced directly into one of the top drums. By introducing the feed water in this manner, troubles have been caused by the corrosive action of the gases contained in the feed water. By the 25 present invention, the feed water is supplied to a pan or trough located in the steam space of the rear steam and water drum, and this trough is connected with downtake tubes of one of the circuits, extending from the top 30 drum to one of the lower mud or sediment drums, in such a manner that the air and dissolved gases are liberated from the feed water before it or as it passes into the circulation, and the feed water so freed from air 35 and gases is led directly to the bottom drum of the circuit which is contacted by the cooler gases from which it passes through the front bank of tubes of this circuit to the front top drum, thence through the common steam and 40 circulating tubes to the rear top drum, and thence into a circuit contacted by hotter gases. In the illustrative embodiment shown in the drawings, the inner circuit is the one that is subjected to cooler gases than the outer circuit and by depositing the mud and

sediment in the drum of the inner circuit, the outer circuit which is subjected to the hotter gases is kept free from mud or sediment and tube troubles are thereby avoided.

In the illustrative embodiment shown in 50 the drawings, a mechanical stoker 10 of the chain grate type is installed in the usual manner at the lower portion of the boiler setting, the front, rear and side walls of which are shown at 11, 12 and 13, respectively. The front steam and water drum 14 and the rear steam and water drum 15, are connected, as usual, by steam and water circulating tubes 16. Two mud or sediment drums 17 and 18 are disposed in a lower 55 plane, the drum 17 being slightly above drum 18, and these drums are provided with valved blow-off pipes 19. An auxiliary drum 20 may be located at the rear of the grate 10, and may be connected by means 60 of a tube or tubes 21 to the mud drum 18.

A bank of downtake tubes 23 connects the steam and water drum 15 to the mud drum 17. A bank of downtake tubes 24 connects the drum 15 to the mud drum 18, a bank of up-take tubes 25 connects the drum 17 to the steam and water drum 14, and a bank of up-take tubes 26 connects the drum 18 to the drum 14. A pipe 27 leads from the steam space of the steam and water drum 15 to the 70 superheater 28. Baffles 30, 31, 32 and 33 are provided, in the usual manner, to direct the hot products of combustion across the water tubes and into the outlet 34 for the gases.

A vertically disposed dash plate 36 with 80 perforations 37 near its upper edge is placed longitudinally within the drum 15 and extends from near the top wall thereof to a distance slightly below the normal water level in this drum, for the purpose of facilitating 85 the separation of the steam and water which enters this drum from the circulating tubes 16. A dry pipe 38 connected to pipe or pipes 27 is located on the other side of the dash plates 36 from the tubes 16, and extends long- 90

gitudinally of the drum 15 in the steam space thereof. A pan or trough 39 is placed in the steam space of the drum 15, and extends therein in a longitudinal direction. Feed water is fed into this pan through the feed water inlet pipe 40. A plurality of tubes 41 lead from the bottom of the pan 39 into the upper ends of some of the downtake tubes 23. With this arrangement, the feed water is first introduced into the pan 39, where air and dissolved gases are liberated, and then the feed water flows downwardly through the tubes 41 into tubes 23 and then into the mud drum 17, thence through the tubes 25 to the front steam and water drum 14, thence through the common steam and water circulation tubes 16 to the rear steam and water drum 15, from whence a portion passes downwardly through the downtake tubes 24 into the lower mud drum 18, through the tubes 26 into the front steam and water drum 14, and through the tubes 16 to the drum 15, the other portion passing downwardly through downtake tubes 23 into the upper mud drum 17, through the tubes 25 to the drum 14. The steam from the tubes 16 flows through the perforations 37 in the baffle 36, and then through the pipes 38 and 27 to the superheater 33.

A single drum with a partition therein may be used instead of the two illustrated drums 17 and 18, the banks of tubes leading to and from the separate portions of the drum being contacted with gases of different temperatures so as to constitute different circuits into one of which the feed water may be introduced after it has been heated as above described.

I claim:—

1. A water tube boiler comprising front and rear steam and water drums, steam and water tubes connecting said drums, at least two lower drums one disposed above the other, sets of uptake tubes and downtake tubes connecting said upper and lower drums, said sets of uptake tubes and downtake tubes being each divided into at least two groups, each of said groups being connected to one of said lower drums, thus affording separate inner and outer circuits, and means for feeding water into the steam space of the rear drum and thence directly into downtake tubes of said inner circuit.
2. A water tube boiler comprising front and rear steam and water drums, steam and water tubes connecting said drums, at least two lower drums one disposed above the other, sets of uptake tubes and downtake tubes connecting said upper and lower drums, said sets of uptake tubes and downtake tubes being each divided into at least two groups, each of said groups being connected to one of said lower drums, thus affording separate inner and outer circuits, and a feed trough within the steam space of the rear steam and

water drum and connections between such feed trough and selected downtake tubes of the said inner circuit.

3. In a boiler, a steam and water drum having a receptacle in the steam space thereof, means for discharging feed water into said receptacle, steam tubes arranged to discharge steam into the steam space of the drum and over the water in said receptacle, and means between said receptacle and the ends of said tubes to separate the steam from the entrained water.

4. In a boiler, a steam and water drum having a receptacle in the steam space thereof, means for discharging feed water into said receptacle, steam tubes arranged to discharge steam into the steam space of the drum and over the water in said receptacle, means between said receptacle and the ends of said tubes to separate the steam from the entrained water, and a dry pipe disposed in the steam space of the drum above the receptacle and having a connection to the steam outlet of the drum.

5. In a boiler, a steam and water drum having a steam inlet and outlet, a receptacle disposed between the inlet and the outlet, means for introducing feed water into said receptacle whereby the steam passing from the inlet to the outlet will come into contact with the water in the receptacle, and means between the inlet and outlet adapted to direct the steam from the inlet into contact with the water in the receptacle on its way to the outlet.

6. In a boiler, a steam and water drum having a steam inlet and outlet, a receptacle disposed between the inlet and the outlet, means for introducing feed water into said receptacle whereby the steam passing from the inlet to the outlet will come into contact with the water in the receptacle, and a plate disposed between the receptacle and the inlet with its lower edge beneath the normal water level in the drum, said plate having a plurality of apertures through which the steam may pass on its way from the inlet to the outlet.

7. In a boiler, a plurality of circulation systems, a steam and water drum common to all said systems and having a pan in the steam space thereof, means for discharging feed water into said pan, and a connection from said pan directly into one of said circulation systems, said connection segregating the feed water from the boiler water in the other systems.

8. In a boiler, a steam and water drum having a pan disposed in the steam space thereof, means for discharging feed water into said pan, water tubes leading from the water space of said drum, and connections leading from the pan directly to said tubes and segregating the water passing through the connections from the water in the drum.

9. In a boiler, a steam and water drum

having a pan disposed in the steam space thereof, a row of tubes extending lengthwise of the drum and connected to the water space thereof, means for passing hot gases in contact with said row, a row of connections leading from said pan directly to tubes in said row, and means for supplying feed water to said pan.

5 In testimony whereof I have signed my
name to this specification.
